GEORGE E. REED AND JOHN W. REED, OF SYRACUSE, NEW YORK

AIR COOLING SYSTEM FOR COMBUSTION ENGINES

Application filed December 27, 1927. Serial No. 242,596.

This invention relates to an air cooling system for internal combustion engines as applied more particularly to motor vehicles.

The main object is to bring the several cylinders into more compact relation than has heretofore been practised in the construction of air-cooled engines and at the same time to reduce the length and weight of the engine by casting all of the cylinders en bloc with relatively short and narrow connecting webs.

Another object is to provide the cylinders with heat-radiating fins of relatively high heat conductivity arranged in parallel spaced relation at right angles to a plane passing through the longitudinal centers or axes of the cylinders and connecting webs so as to afford a far greater heat transfer area than has heretofore been possible in engines having their cylinders cast en bloc.

Another object is to provide the cylinders with a removable head having similar heat-radiating fins preferably in vertical alignment with the fins of the cylinders so as to form continuous vertical air passages between the fins of both sets.

A further object is to bring the intake and exhaust ports and their corresponding valves as nearly as possible in the longitudinal center of the head and to converge the side walls of the head toward said ports to reduce to a minimum the conductive distance between the centers of the exhaust valves and the adjacent cooling fins and thereby to expedite the dissipation of the heat from the heat at the sources of maximum temperature.

Another object is to provide the engine with an air-jacket of sheet metal of relatively high heat conductivity extending along the opposite sides and rear end of the cylinders and across the outer edges of the fins in heat transfer relation thereto to form suitable chambers for the circulation of air therethrough and through the spaces between the fins for cooling purposes.

A further object is to arrange the valves and ports in planes at an acute angle to each other merging in the longitudinal center of the cylinder head to further facilitate

the cooling of the head and particularly the walls of the exhaust ports therein.

Other objects and uses relating to specific parts of the engine and cooling system will be brought out in the following description.

In the drawings:

Figure 1 is a transverse vertical sectional view through one of the cylinders and crank case of an internal combustion engine and air-circulating passages together with the heat transfer fins and one of the ports and valve for controlling the same, together with the cam shaft and its inclosing case and the means for clamping the cylinder head to the cylinder block.

Figure 2 is a side elevation, partly in section and partly broken away, of the engine and cooling system shown in Figure 1 in which the four cylinders are cast en bloc.

Figure 3 is a horizontal sectional view taken in the plane of line 3—3, Figure 2.

As illustrated, this engine comprises a plurality of, in this instance four, upright cylinders —1— which are cast en bloc from suitable metal such as cast iron, with relatively short and narrow connecting webs —2— and —2'— in a plane passing through the vertical axes of the cylinders to bring the cylinders in close compact relation and thereby to reduce the length and weight of the engine and at the same time exposing practically the entire peripheral areas of the several cylinders to the cooling influence of the surrounding atmosphere for dissipating the heat therefrom. That is, the transverse width of the webs 2 and 2' is less than 40% of the diameter of the bore of any one of the cylinders, this ratio taken in connection with the peculiar distribution and relative widths of the heat radiating fins being found to be most efficient in maintaining the temperature of the cylinders below a safe limit or more specifically below the limit of flash ignition of the piston lubricating oils as will be hereinafter more fully described.

The cylinders —1— are mounted upon a crank case —3— in which the crank shaft —4— is journaled, said crank shaft being connected by pitmen —5— to suitable pis-

tons —6— for reciprocating the latter with in their respective cylinders —1—.

The upper ends of the cylinders —1— are capped by a suitable head —7— which is held in place by clamping bolts —8— having their lower ends engaged with the undersides of lugs —9— on opposite sides of the intermediate portion of the cylinders and their upper ends engaged with the upper faces of lugs —10— on opposite sides of the head —7— as shown more clearly in Figure 1.

The lugs —9— at each side of the cylinder are preferably arranged in pairs, those of each being spaced apart to permit the lower ends of the bolts to be placed between them with the head of the bolt engaged with the underside of the corresponding pair of lugs —9—.

In like manner the lugs —10— at each side of the longitudinal center of the head —7— are arranged in pairs, those of each pair being spaced apart to receive the upper ends of the bolts —8—, having their nuts as —8'— engaged with the upper faces of the corresponding pair of lugs —10— so that when the nuts —8'— are loosened the bolts may be withdrawn laterally from their respective lugs —9— and —10—.

The bolts —8— are preferably flat in cross section and arranged edgewise with reference to the longitudinal center of the engine so that they may be conveniently placed between adjacent cooling fins on the cylinder —1— and its head —7—.

It is, of course, understood that when the head —7— is clamped to the upper end of the cylinders —1— suitable packing will be employed to form a gas-tight joint.

The head —7— is provided in its lower side with chambers —11— alined with the combustion chambers as —12— of the cylinders —1— and having their opposite sides converging upwardly, each chamber —11— being provided with an intake port —13— and an exhaust port —14— extending upwardly from the apex thereof at an angle to and to one side of the axis of the cylinder.

These ports —13— and —14— are controlled by separate valves —15— and —16— having their stems extending upwardly from said apex through suitable guide openings in the upper walls of their respective ports at an angle to and to the other side of the axis of the cylinder and are yieldingly held in closed positions by springs —17—, Figure 1.

The ports —13— and —14— and the corresponding valves —15— and —16— are therefore disposed in upwardly diverging planes intersecting each other in the longitudinal center of the head so that the portion of the head —7— in the horizontal plane of the valves —15— and —16— is contracted transversely to bring the rela-

tively thin side walls thereof into close heat-transfer relation to those parts of the engine which are subjected to the highest temperatures.

A cam shaft housing —18— is removably secured to the top face of the head —7— to inclose the upper ends of the valve stems and also to receive and inclose a cam shaft —19— and its cams —20— which serve to open the valves —15— and —16— against the action of their springs —17— as the cam shaft —19— is rotated in suitable time relation to the movements of the pistons —6— as usual in four cycle engines of this type.

Air cooling system

The upper ends of the cylinders —1— in which the combustion chambers —12— are formed and also the connecting webs —2— and —2'— are provided with vertically disposed fins —21— arranged in uniformly spaced parallel relation lengthwise of the engine or at right angles to a plane passing through the axes of the cylinders and having their inner edges cast into the peripheries of the cylinders and opposite upright faces of the webs and their outer edges disposed in vertical planes parallel with the plane passing through the axes of the cylinders.

The upper edges of the fins —21— are disposed in substantially the same horizontal plane as the upper ends of the cylinders while their lower edges are disposed in a horizontal plane closely adjacent but slightly above the lower ends of the combustion chambers —12— to afford ample space for the circulation of air from the underside upwardly through the spaces between the fins.

In like manner the head —7— is provided with vertically disposed fins —22— projecting from opposite sides thereof in uniformly spaced parallel relation lengthwise of the engine and extending from the upper ends of the cylinders some distance above the contracted portion of the head in which the valves —15— and —16— are seated.

The outer edges of the upper portions of the fins —22— are disposed in vertical planes parallel with and some distance from the corresponding sides of the head —7— while the outer edges of the lower portions of said fins —22— are flared outwardly and downwardly to approximately the width of the underlying fins —22— on the cylinders to form continuations thereof.

That is, the fins —22— on both sides of the head —7— are preferably in vertical alinement with the fins —21— on corresponding sides of the cylinders —1— and webs —2— and —2'— so as to form intervening vertical air passages through which the air may be circulated for cooling purposes.

The inner edges of the fins —21— and —22— are integrally united to the cylinders —1— and to the head —7— respectively during the process of casting those parts and are preferably made of copper or other suitable material having a high degree of heat conductivity capable of expeditiously dissipating the heat transferred thereto from the cylinders and head.

It will be observed upon reference to Figure 3 that the webs —2— and —2'— are relatively narrow as compared with the diameter of the cylinders to allow the fins to be continued around practically the entire peripheries of the cylinders and thence along the webs in substantially the same spaced relation for producing a greater combined heat transfer area than has heretofore been practiced. That is, the fins 21 and 22 are made of sheet metal and of far greater heat conductivity than the cast metal of the cylinders and webs and contribute materially in preventing the rise of temperature of the cylinders above a safe limit previously mentioned.

Furthermore, the opposite heat radiating surfaces of these fins are parallel and serve the double purpose of keeping the temperature of the cylinders within safe limits and also of reducing the frictional resistance to the passage of the cooling air along and between the fins.

Another feature of the invention lies in the fact that the combined widths of the opposite surfaces of the fins within an arc of approximately 45 degrees from the center line of the engine cylinders is more than six times the diameter of the bore of any one cylinder and constitutes a further means for keeping the temperature of the cylinders within safe limits, this approximate ratio having been demonstrated to be practical and most efficient.

The outer edges of the fins leading from the end webs —2— are connected by sheet metal plates —23—, preferably of the same material such as copper, to the outer ends of the fins which extend outwardly from the central longer web —22—.

These plates —23— extend downwardly from the upper ends and across the outer edges of the cylinder fins —21— to suitable seats —24— on opposite sides of the upper portion of the crank case —3— so as to lie in vertical planes some distance from the walls of the cylinders and parallel with a plane passing through the vertical axes of said cylinders thereby forming air chambers —25— extending lengthwise of the engine from front to rear between the lower edges of the fins —21— and upper walls of the crank case —3— as shown in Figure 1.

Additional plates —23'— are extended across the outer edges of the lower portions of the fins —22— in heat transfer relation

thereto and in vertical alinement with the corresponding side plates —23— to form continuations thereof, the upper edges of said plates —23'— converging upwardly to conform to the upwardly converging outer edges of the adjacent fins.

These chambers —25— communicate with the vertical spaces between the fins —21— and —22— so that cold air entering both chambers may find free exit upwardly through the spaces between the fins.

Any suitable means may be employed for forcibly circulating atmospheric air through the chambers —25— and thence upwardly through the spaces between the fins —21— and —22— which spaces are open at the top to allow free exit of the heated air.

As illustrated, this circulating means comprises a rotary fan —27— mounted upon an upright shaft —28— on the front end of the engine, said fan being inclosed within a case —29— forming a continuation of the side plates —23—.

The lower and upper walls of the fan case —28— are provided with circular openings —30— concentric with the rotary fan —27— to admit atmospheric air from the lower and upper ends of the fan case into the interior thereof where it is forcibly circulated through both of the chambers —25— and thence upwardly through the spaces between the fins —21— and —22—.

The rearmost fins as —21'— are extended downwardly across the rear ends of the chambers —25— to close the same and thereby to cause the deflection of the currents of air from said chambers upwardly between the remaining fins —21— and —22—.

That is, the side plates —23'— and —23— extend downwardly from the intermediate portions of the fins —22— to the top of the crank case —3— and across the outer edges of the fins —21— and —22— and have their rear ends connected to the corresponding outer edges of the rearmost fins —21'— while their front ends are connected to the two opposite sides walls of the fan case —29— to form the air chambers —25— and thereby to confine and direct the circulation of air from the fan case —29— through the chambers —25— beneath the fins —21— and thence upwardly between the fins —21— and —22—.

The rearmost fins —21'— extend the full width of the side plates —23— and have their outer edges united thereto to form the rear end walls of the chambers —25— which impedes the rearward movement of the air currents and causes the air to pass upwardly from the chambers —25— between the chambers —21— and —22— to escape to the atmosphere at the top of the fins —22—.

These side plates —23'— and —23— to-

gether with the rearmost fins —21'— also are made of thin sheet copper of high heat conductivity to receive the heat from the fins —21— and —22— and thereby greatly 5 add to the heat transfer area of the cooling system.

The outer edges of two of the fins —21— leading from opposite sides of the webs —2— are connected by vertical plates —31— to the outer edges of two of the fins —21— leading from opposite sides of the next web —2'— and extend across the outer edges 10 of the intervening fins in spaced relation to the plate —23— to receive heat from said intervening fins and from the webs and thereby to further increase the heat transfer 15 area of the cooling system.

The head —7— which is common to all 20 of the cylinders is provided with suitable sockets —32— for receiving spark plugs, one for each cylinder. As previously stated, the clamping bolts —8— are flat transversely and arranged at diametrically opposite 25 sides of each cylinder, the purpose in flattening the bolts being to enable them to pass between adjacent fins —21— and —22— of the cylinders —1— and head —7— respectively as shown more clearly in Figure 3.

The lower end of the fan shaft —28— 30 may be operatively connected to the crank shaft —4— of the engine by any suitable power transmitting device arranged within a suitable gear case —33— on the front end of the crank case —3—.

35 Operation

When the engine is in operation the fan —27— will be rotated at suitable speed to 40 take in the cool atmospheric air through the openings —30— and to circulate said air rearwardly through the chambers —25— and thence upwardly between and against the fins —21— and —22— which rapidly 45 take up the heat transferred thereto from the engine cylinders —1— and head —7— and owing to the large surface areas of the fins together with their high heat conductivity, the heated air transferred thereto is rapidly dissipated and allowed to escape at 50 the upper ends of the fins aided by the force of the air currents produced by the operation of the fan —27—, it being understood that the plates —23— and —31—, together with the rearmost plates —21'— add materially to the rapidity of heat transfer and dissipation of the heat to the atmosphere and that the relatively narrow webs —2— and —2'— connecting the cylinders and to which some of the fins are connected, additionally expedite the transfer of heat from 55 the cylinders to the atmosphere.

It will also be observed that the particular parallel vertical relation of the fins and their projection from the cylinders and webs in 60 the manner described enables those fins to be

extended laterally indefinite distances, but preferably within the width of the crank case without interference with each other thereby producing a maximum heat transfer area capable of dissipating the heat developed by the operation of the engine under all climatic temperatures in addition to affording free natural upflow of the air between and against the fins aided or expedited by the forcible circulation of the air 75 through the operation of the rotary fan —27—.

We claim:

1. In an air-cooling system for an upright internal combustion engine having a cast 80 metal cylinder, a plurality of vertically disposed sheet metal fins projecting outwardly from the opposite sides of the cylinder in parallel spaced relation and having their lower ends terminating in a plane above the 85 lower end of the combustion chamber of the cylinder.

2. An internal combustion engine cylinder having lengthwise relatively narrow webs projecting from diametrically opposite sides thereof, lengthwise fins projecting from opposite sides of the cylinder and webs in parallel spaced relation at right angles to a plane passing through the axis of the cylinder and webs, and a heat transfer plate 95 connecting the outer upright edges of the web-fins.

3. An internal combustion engine cylinder having lengthwise relatively narrow webs projecting from diametrically opposite sides thereof, and lengthwise vertically disposed fins projecting from opposite sides of the cylinder and webs in parallel spaced relation at right angles to a plane passing through the axis of the cylinder and webs, 100 said fins having their lower ends terminating in a plane above the lower ends of the combustion chambers of said cylinders.

4. An internal combustion engine comprising a plurality of cylinders arranged in 110 line and connected by intervening relatively narrow lengthwise webs, and fins projecting from the cylinders and webs in parallel spaced relation at right angles to a plane passing through the axis of the cylinders 115 and a heat-transfer plate extending across the outer upright edges of the cylinder fins and connected to the web-fins.

5. An internal combustion engine comprising a plurality of upright cylinders arranged in line, vertically disposed sheet metal fins projecting outwardly from opposite sides of the cylinders in parallel spaced relation, and upright sheet metal plates in direct contact with the outer edges of the 125 end fins of each cylinder, and engine-driven means for circulating air vertically through the spaces between the fins.

6. In a multiple cylinder internal combustion engine having a removable head, and 130

5 fins projecting from opposite sides of the head in parallel spaced relation, said head having tapered ignition chambers forming continuations of the combustion chambers of the cylinders, each chamber having an inlet port and an exhaust port in its apex, self-closing valves for said ports, and engine-driven means for opening the valves.

7. In a cooling system for internal combustion engines, the combination with an upright cylinder having webs of unequal width projecting from diametrically opposite sides thereof, said cylinder having an intake port adjacent the wider web and an exhaust port adjacent the narrower web, and vertically disposed fins projecting outwardly from opposite sides of the webs in parallel spaced relation and at right angles to a direct line passing through the axis of the cylinders and centers of both webs.

8. In a cooling system for internal combustion engines, the combination with an upright cylinder having webs of unequal radial length projecting from diametrically opposite sides thereof, said cylinder having an intake port adjacent the web of lesser radial length and an exhaust port adjacent the web of greater radial length, and vertically disposed fins projecting laterally from opposite sides of the webs in parallel spaced relation, the web of greater radial length having a greater number of laterally projecting fins than the one of lesser radial length.

35 9. An internal combustion engine comprising a plurality of cast-metal cylinders in line and cast en bloc with intervening webs along the center line, said webs being of considerably less width than the bore of any one of the cylinders, and sheet metal fins, of greater heat conductivity than the cast metal, projecting outwardly from opposite sides of the cylinders and webs in spaced parallel relation at right angles to the center line of the cylinders.

45 10. An internal combustion engine as in claim 9 in which the opposite surfaces of the fins are parallel.

11. An internal combustion engine as in claim 9, the ratio of combined width of the opposite surfaces of the fins within an arc of 45 degrees from said center line to the diameter of the bore of any one cylinder is greater than six to one.

55 12. In an upright multiple cylinder internal combustion engine having a removable head, said head having vertically disposed sheet metal fins projecting outwardly from opposite sides of the head in parallel spaced relation and at right angles to a plane passing through the axes of said cylinders.

65 13. In an upright multiple cylinder internal combustion engine having a head and vertically disposed sheet metal fins project-

ing from opposite sides of the head in parallel spaced relation and at right angles to a plane passing through the axes of said cylinders, said head having upwardly tapered ignition chambers forming continuations of the combustion chambers of the cylinders, each chamber having an intake port and an exhaust port in its apex, self closing valves controlling said ports, and engine driven means for opening said valves.

75 14. In a multiple cylinder internal combustion engine having a tapered head, upright fins projecting from opposite sides of the cylinder in parallel spaced relation and clamping bolts between adjacent fins and having their lower ends operatively connected to the cylinders near the lower ends of the combustion chambers and their upper ends movable laterally into and out of engagement with the head for holding and releasing the head in and from its operative position, said clamping bolts being of less width than the distance between adjacent fins to prevent contact therewith.

80 15. An internal combustion engine comprising a plurality of cast metal cylinders in line and cast en bloc with intervening webs along the center line, the webs of each cylinder being of unequal width and length, the wider webs having the shorter length, 95 and sheet metal fins projecting outwardly from opposite sides of the cylinders and webs in equal spaced parallel relation at right angles to a plane passing through the axis of the cylinders.

90 16. An internal combustion engine as in claim 15 in which each of the cylinders are provided with an intake port adjacent the web of lesser length, and an exhaust port adjacent the web of greater length.

105 In witness whereof we have hereunto set our hands this 16th day of December, 1927.
